(57) **CLAIM**

The ornamental design for a vehicle kitchen cabinet, as shown.

DESCRIPTION

FIG. 1 is an overall view of a vehicle kitchen cabinet showing my new design;

FIG. 2 is another overall view of a vehicle kitchen cabinet thereof from the bottom;

FIG. 3 is a front view thereof;

FIG. 4 is a back view thereof;

FIG. 5 is a left view thereof;

FIG. 6 is a top view thereof;

FIG. 7 is a bottom view thereof;

FIG. 8 is a zoom-out view showing a first use state;

FIG. 9 is a zoom-out view showing a second use state; and,

FIG. 10 is a zoom-out view showing a third use state.

The broken lines depict portions of the designs but form no part of the claimed disclosure.
